UNITED STATES PATENT OFFICE.

HUGH V. CROZIER, OF MORRILLTON, ARKANSAS.

FAUCET.

SPECIFICATION forming part of Letters Patent No. 537,755, dated April 16, 1895.

Application filed February 24, 1894. Serial No. 501,381. (No model.)

To all whom it may concern:

Be it known that I, HUGH V. CROZIER, a citizen of the United States, residing at Morrillton, in the county of Conway and State of 5 Arkansas, have invented a new and useful Faucet, of which the following is a specification.

This invention relates to faucets, and it has for its object to provide certain improvements 10 in faucets of that character which are adapted to bore their own openings into the barrel or other receptacle into which they are fitted.

To this end the main and primary object of 15 the present invention is to provide a simple and inexpensive faucet provided with means for easily turning the same into a keg or barrel after placing such receptacle for use, while at the same time preventing the liquid from escaping during the operation of boring the 20 hole.

With these and other objects in view, which will readily appear as the nature of the invention is better understood, the same consists in the novel construction, combination, 25 and arrangement of parts hereinafter more fully described, illustrated, and claimed.

In the accompanying drawings:—Figure 1 is a perspective view of a self-boring faucet constructed in accordance with this invention. 30 Fig. 2 is a central longitudinal sectional view thereof. Fig. 3 is a sectional view of one end of a barrel showing my improved faucet properly in position as fitted to the barrel head. Fig. 4 is a similar view including a modified 35 form of closure sleeve or thimble and a different valve or cut-off device.

Referring to the accompanying drawings, A represents the faucet tube constructed in suitable lengths adapting the same for use in 40 connection with various receptacles. The said faucet tube has attached to the outer end thereof the operating handle B, extending to either side thereof and providing a firm grasp for the hand while turning the faucet into 45 the head of a barrel or keg X, such as illustrated in some of the figures of the drawings.

The straight faucet tube A, is slightly reduced at its other end as at C, and is exteriorly threaded to insure the entrance of the 50 tube sufficiently far within the barrel or keg to uncover the opposite inlet openings D,

formed in such exteriorly threaded and reduced end of the tube, and beyond the exteriorly threaded portion of the tube the same is extended into or is provided with a boring 55 bit or auger E, which provides simple and efficient means for boring a hole into the receptacle and providing for the insertion of the faucet into such receptacle for use.

The exteriorly threaded end of the faucet 60 tube has been described as slightly reduced to form a slightly tapered portion on which tightly fits the sliding closure sleeve or thimble F. The closure sleeve or thimble F, is adapted to slide on the faucet tube under force, and 65 is provided with a stop flange G, at one end which is adapted to engage at one side of the discharge spout H, fitted into the faucet tube near the outer handle end thereof, and when such closure sleeve or thimble is forced up to 70 a position against the discharge spout H, the other end of said sleeve or thimble will be disposed at one side of the inlet openings D, so as to uncover the same. Now it will be obvious that with the closure sleeve or thimble 75 set in a position near the outer point end of the boring bit or auger E, the same will close or cover the openings D, and one end of the sleeve or thimble will always press tightly against the outer side of the barrel or keg as 80 the bit or auger continues to bore its hole thereinto, and this provides efficient means for packing the opening being bored and preventing any leakage. As the bit or auger passes into the receptacle and the threads C, 85 engage the opening bored thereby, the sleeve or thimble F, will be forced out toward the outer handle end of the tube and against the spout H, and by a continued turning of the tube inner end of the sleeve or thimble 90 will be firmly pressed into or around the outer edge of the opening so as to form a substantial bushing or packing therefor.

The closure sleeve or thimble F, may be constructed of any suitable non-corrosive 95 material, and the construction thereof may be slightly modified without altering the use thereof, and by reference to Fig. 4, of the drawings, it will be seen that one end of the sleeve may be enlarged to form a cup or funnel-head J which presses directly against the barrel to receive the chips or borings, while 100

at the same time forming a packing to prevent leakage. In this modification the other part of the sleeve or thimble snugly embraces the faucet tube as already described.

- 5 While different means may be provided for cutting off the flow through the discharge spout H, I preferably employ the turning cut-off plug K, turning in the outer open end of the faucet tube and provided with an inner 10 narrowed valve tongue L, which is adapted to be turned over and away from the inner end of the spout H, to provide for cutting off the flow and for allowing the liquid to pass out of the spout, and to the outer end of said 15 turning plug is attached the finger knob M, which is grasped by the fingers of the hand to properly manipulate said cut-off or valve plug. The plug K, has a wedging fit sufficiently tight within the outer open end of the 20 faucet tube to prevent the same from being forced out by liquid pressure, while at the same time not interfering with the turning of the plug to control the discharge through the spout H.
- 25 In Fig. 4, of the drawings I have shown a slightly modified form of cut-off in which a cut-off plug N, works through an opening in one side of the faucet tube and into the discharge spout H. The plug N, has attached to the 30 outer end thereof the press lever O, pivotally supported at one side of the faucet tube and provided with a finger flange P, which is depressed to lift the plug out of the discharge spout and under which is arranged the spring 35 Q, to normally hold the plug N, in the spout H, and cut off the flow of the liquid.
- Other forms of cut-offs and other modifications might readily suggest themselves to those skilled in the art, and I will therefore 40 have it understood that changes in the form, proportion and the minor details of construction may be resorted to without departing from the principle or sacrificing any of the advantages of this invention.
- 45 Having thus described the invention, what is claimed, and desired to be secured by Letters Patent, is—

1. In a self-boring faucet, the combination of the faucet tube having inlet openings at one end, and a boring bit or auger beyond the 50 inlet openings, and a closure sleeve or thimble mounted to slide on said tube to cover and uncover said openings, said sleeve or thimble being provided at one end with a cup portion to fit over the hole bored by the bit or auger, 55 substantially as set forth.

2. In a faucet of the class described, the tube having inlet openings at one end, and a boring bit or auger extended beyond the inlet openings, and a flanged closure sleeve or 60 thimble mounted to slide on said tube and adapted to be limited in its movement by the discharge spout of the faucet, substantially as set forth.

3. In a self boring faucet, the combination 65 of the faucet tube having a reduced exteriorly threaded portion, inlet openings in said threaded portion, and a boring bit or auger projected beyond said threaded portion, and a flanged closure sleeve or thimble mounted 70 to slide on said tube and adapted to be limited to a movement which brings one end thereof at one side of said inlet openings, substantially as set forth.

4. In a self boring faucet, the combination 75 of the straight faucet tube having a discharge spout projected from one side, inlet openings, and a boring bit or auger projected beyond said inlet openings, an operating handle attached to the other end of the tube, a suitable 80 cut-off for the discharge of the faucet tube, and a closure sleeve or thimble mounted to slide on said tube at one side of the discharge spout and provided with a cup portion at one end adapted to fit over the hole bored by said 85 bit or auger, substantially as set forth.

In testimony that I claim the foregoing as my own I have hereto affixed my signature in the presence of two witnesses.

HUGH V. CROZIER.

Witnesses:

CHAS. JACOBSON,
E. O. RAMON.
